(57) **CLAIM**

The ornamental design for a button area of cleaning robot as shown and described.

DESCRIPTION

The patent or application file contains at least one drawing executed in color. Copies of this patent or patent application publication with color drawing(s) will be provided by the Office upon request and payment of the necessary fee.

1. Button area of cleaning robot

1.1 : Front

1.2 : Enlarged

1.3 : Perspective

1.4 : Enlarged

1.5 : Perspective

Reproduction 1.1 is a front view showing a button area of cleaning robot, reproduction 1.2 is an enlarged view of part A boxed and marked in reproduction 1.1, reproduction 1.3 is a perspective view showing the button area of cleaning robot, reproduction 1.4 is an enlarged view of part B circled and marked in reproduction 1.3, and reproduction 1.5 is another perspective view of the cleaning robot; those portions of the cleaning robot covered by translucent red color

(Continued)

in the reproductions form no part of the claimed design, while only the uncovered button area of the cleaning robot is claimed.
